CLAIM

The ornamental design for a head for a pole-type sander, as shown and described.

DESCRIPTION

FIG. 1 is a left side elevational view of a head for a pole-type sander showing my new design;

FIG. 2 is a top plan view thereof;

FIG. 3 is a right side elevational view thereof;

FIG. 4 is a front elevational view thereof;

FIG. 5 is a rear elevational view thereof;

FIG. 6 is a bottom plan view thereof;

FIG. 7 is a top perspective view thereof.

Fig. 1.Fig. 2.Fig. 3.Fig. 4.Fig. 5.Fig. 6.
